UNITED STATES PATENT OFFICE.

JESSE B. PICKELSMER, OF BREVARD, NORTH CAROLINA.

RAILWAY-TIE PLATE.

Application filed October 24, 1925. Serial No. 65,736.

This invention relates to a plate for use in connection with railway ties whereby trespassing can be prevented.

A further object is to provide a tie plate which serves to engage and support those portions of rails extending between the ties.

Another object is to provide tie plates which, when assembled, constitute top shields for the ties, the said plates serving to shed moisture and to protect the ties from injury by objects striking thereagainst.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawing the preferred form of the invention has been shown.

In said drawings,

25 Figure 1 is a plan view showing some of the tie plates in position on ties and in engagement with rails.

Figure 2 is a vertical transverse section, one of the rails being removed, said section being taken on the line 2—2, Figure 1.

Figure 3 is a section on line 3—3, Figure 1.

Figure 4 is a section on line 4—4, Figure 1.

35 Figure 5 is a section on line 5—5, Figure 1.

Referring to the figures by characters of reference 1 designates a shield plate so proportioned as to extend throughout the length 40 of a tie T and over approximately one-half the width of the tie. This plate is provided along the upper portion of one edge with an overhanging flange 2. A similar plate 3 is adapted to rest upon the next adjoining tie

45 and extends throughout the length thereof and over approximately one-half the width of the tie. This plate 3 has a projecting flange 4 along its longitudinal edge adapted to rest on the tie. The two plates 1 and 3 are in-

50 tegral with parallel rail supporting plates 5 each of which has longitudinal flanges 6 which are inturned as shown particularly in Figure 2 so as to overhang and retain the base flanges of a rail R. The top faces of the

55 rail engaging plates 5 aline with the bottom faces of channels 7 formed in the plates 1

and 3 and extending transversely thereof, these channels being adapted to receive the base flanges of the rails R. The plates 5 are formed with shoulders 8 constituting abutments for the ties T so as to prevent the ties from creeping relative to each other. This is clearly illustrated in Figures 3 and 4.

Prongs 9 are formed on or connected to the plates 1 and 3 and extend upwardly 60 therefrom so as to prevent trespassing. At desired points apertures 10 can be provided in these plates for the reception of spikes whereby the plates may be attached securely to the ties. Ribs 11 can also be extended

10 downwardly from the plates for engaging the ties and preventing the plates from creeping relative thereto. It is to be understood that a plate made up of the parts 1, 3 and 5 is provided for every two ties. The mem-

15 bers 1 and 3 are placed on the ties with the plates 5 between the ties and the shoulders 8 abutting against said ties. Another tie plate is then placed upon one of said ties and the next adjoining tie so that the flange

20 2 on one plate 1 will lap the flange 4 on the next adjoining plate 3. This arrangement is continued throughout the length of the track and with the plates secured in position

25 they serve to protect the ties, to shed moisture therefrom, and to embrace and support the rails. Spikes 12 such as usually employed can be provided for fastening the rails to the plates, these spikes being driven

30 through apertures 13 in the plates and into 90 the ties T.

The plates 1 and 3 can be thickened adjacent the point where they are engaged by the rails and the outer thickened portions can be extended upwardly against the outer 95 sides of the rail webs and under the heads of the rails so as to constitute braces. This has been clearly indicated at 14. This rail and brace has been indicated in section in Figure 5.

100 What is claimed is:

1. The combination with tie engaging plates, each adapted to extend throughout the length of an engaged tie and over one-half the width of said tie, of rail engaging 105 and supporting plates connecting the tie engaging plates, and flanges extending throughout the length of the rail engaging and supporting plates for embracing the base flanges of rails on the plates.

110 2. The combination with tie engaging plates each having a longitudinal flange,

the flange on one plate being below the plane of the flange on the other plate, of rail engaging and supporting plates connecting the tie engaging plates, flanges thereon for bracing the base flanges of rails.

3. The combination with tie engaging plates each having a longitudinal flange, the flange on one plate being below the plane of the flange on the other plate, of rail

engaging and supporting plates connecting the tie engaging plates, flanges thereon for embracing the base flanges of rails, and depending tie engaging ribs upon said plate.

In testimony that I claim the foregoing as my own, I have hereto affixed my signature.

JESSE B. PICKELSMER.
